UNITED STATES PATENT OFFICE.

CLARENCE B. GORE, OF CHICAGO, ILLINOIS.

DESIGN FOR AN EMBLEM BUTTON.

58,436.

Specification for Design.

Patented July 19, 1921.

Application filed July 12, 1920. Serial No. 395,777. Term of patent 14 years.

To all whom it may concern:

Be it known that I, CLARENCE B. GORE, a citizen of the United States, residing at Chicago, in the county of Cook and State of Illinois, have invented a new, original, and ornamental Design for Emblem Buttons, of which the following is a specification, reference being had to the accompanying drawing, forming part thereof.

The figure is a plan view of the button showing my new design.

I claim:

The ornamental design for an emblem button, as shown.

CLARENCE B. GORE.

Witnesses:

EDNA B. PETERSON,
LETTY M. PARNHAM.
